Patented Feb. 24, 1920.

UNITED STATES PATENT OFFICE.

FERDINAND KRONENBERGER, OF NEW YORK, N. Y.

FILLER FOR SHIPPING-PACKAGES.

1,331,509.

Specification of Letters Patent.

Patented Feb. 24, 1920.

Application filed November 10, 1915. Serial No. 60,640.

To all whom it may concern:

Be it known that I, FERDINAND KRONENBERGER, a citizen of the United States, residing at the city of New York, county of Bronx, and State of New York, have invented a certain new and useful Filler for Shipping-Packages, of which the following is a specification.

This invention is a means for shipping breakable or perishable articles, and while said invention is useful in the transportation of articles in many lines of industry and trade, it is more particularly adapted for breakable substances like eggs, breakable articles such as incandescent lamp bulbs, and perishable fruits or vegetables which are liable to become injured or bruised in shipment.

The novel features and advantages of the invention will be apparent from the following detailed description.

In the drawings,

Figure 1 is a perspective view illustrating a top filler and an intermediate filler, the two fillers being relatively separated in order to illustrate the slotted portions adjacent the contacting edges of the fillers when superposed.

Fig. 2 is a vertical section through a portion of a packing case equipped with superposed fillers in accordance with this invention.

A, B designate fillers or cell cases adapted to be positioned at the bottom and top, respectively, of a shipping package, and C designates an intermediate filler or cell case, any desired number of which cell cases C may be employed between the cell cases A, B.

Each filler A, B or C embodies strips a b and c d, the strips c d crossing the strips a, b, and said crossing strips being attached or fastened in any preferred way, such as by interlocking the strips at their points of intersection in a manner well known to those skilled in the art. The strips a b constitute a pair positioned in close relation, there being any desired numbers of pairs a b used according to the dimensions and capacity of the filler. Similarly the strips c d constitute a pair of crossing strips, there being any desired number of pairs of such strips c d. The pairs of strips intersect so as to form small compartments or cells D and larger cells E.

The salient feature of the invention con-

sists in the use of slits F extending inwardly from the contacting edges of the fillers.

Said fillers A B C are positioned in superposed order within the packing box or case G as shown in Fig. 2, from which it will be noted that the top edge of filler C is in contact with the bottom edge of filler B, whereas the bottom edge of filler C is in contact with the top edge of filler A. The slits F extend inwardly of the fillers from the contacting edges thereof, and these slits produce yieldable tongues adapted for contact with the articles to be packed in the fillers, whereby the pressure of said articles displaces the tongues so as to press the tongues partially into the smaller cells D of said fillers, see Fig. 2.

The articles packed into the fillers are firmly held by the slotted yieldable portions F under the pressure applied to the fillers, so that the articles are retained immovably in position during the shipment of the package.

It will be noted that the articles packed in the cells E of the filler displace the tongues formed by the slits into the smaller cells D, and thus the articles cannot interfere or contact one with the other, and all the larger cells E may be used, if desired, for the reception of the articles.

Although I have shown and described each filler as comprising double strips a b and c d to produce large cells and small cells, it is apparent that slotted single strips, such as a, c, may be used to the exclusion of strips b, d, thus resulting in single cells in the filler, all the cells being uniform in size. In view of the obviousness of this organization of single slotted strips, I have not considered it essential to illustrate the same.

Again, it is apparent that any desired number of fillers may be used in a packing box or case, such as the three fillers A B C of Fig. 2, it being understood that only two fillers may be used in a small package or more than four fillers used in larger packages.

Having thus fully described the invention, what I claim as new, and desire to secure by Letters Patent is:

1. In a shipping package, a filler comprising pairs of crossing attached strips forming large and small individual cells, some of said strips being slotted inwardly from their contacting edges, the slotted portions produc-

ing tongues which are yieldable under pressure and constitute gripping means for the articles to be contained in the cells, whereby the pressure of the articles inserted in the 5 larger cells displaces the yieldable tongues partially into the smaller cells.

2. In a shipping package, a filler comprising a row of yieldable strips crossed and forming individual cells, said strips being 10 slitted inwardly from their contacting edges

to form yielding gripping means at opposite edges of the filler, the yielding portions adapted to give under pressure applied thereto by the articles and the articles adapted to be held by the yielding portions 15 of superposed fillers.

In testimony whereof I have hereunto signed my name.

FERDINAND KRONENBERGER.
